(57) **CLAIM**

The ornamental design for a dining table, as shown and described.

DESCRIPTION

FIG. 1 is a perspective view of a dining table in accordance with the present invention;

FIG. 2 is a front view of the dining table, the back of the dining table being a mirror image thereof;

FIG. 3 is a top view of the dining table, the bottom of the dining table is not illustrated as it forms no part of the present invention; and,

FIG. 4 is a right side view of the dining table, the left side view being a mirror image thereof.
